UNITED STATES PATENT OFFICE.

HARRY L. ROBY, OF BARNESTVILLE, OHIO.

DESIGN FOR A CIGAR-PACKAGE.

51,214.

Specification for Design. Patented Aug. 28, 1917.

Application filed July 11, 1916. Serial No. 108,751. Term of patent 7 years.

To all whom it may concern:

Be it known that I, HARRY L. ROBY, a citizen of the United States, residing at Barnesville, county of Belmont, and State of Ohio, have invented a new, original, and ornamental Design for Cigar-Packages, of which the following is a specification, reference being had to the accompanying drawings, forming part thereof.

In the drawing:

Fig. 2 is an outer end view thereof.

I claim:

The ornamental design for a cigar package, as shown.

HARRY L. ROBY.
